SAFETY HANDLE

Stephen A. Young, Monticello, Ind. (Flora, Ind.)

Filed Oct. 17, 1958, Ser. No. 53,016

Term of patent 14 years

(Cl. D91—3)

Fig. 1

Fig. 4

Fig. 2

Fig. 5

Fig. 3

Figure 1 is a top plan view of the safety handle embodying my new design.

Figure 2 is a side elevation of the same.

Figure 3 is a bottom view of the same.

Figure 4 is an end elevation of the same looking from the right hand end of Figure 1.

Figure 5 is an end elevation of the same looking from the left hand end of Figure 1.

I claim:

The ornamental design for safety handle, substantially as shown.
